NON-RETURNABLE BOTTLE CARRIER

Henry L. Metzger, Castleton-on-Hudson, N. Y., assignor to Fort Orange Paper Company, Castleton-on-Hudson, N. Y., a corporation of New York

Application May 10, 1954, Serial No. 428,522

3 Claims. (Cl. 220—113)

This invention relates to bottle carriers, having particular reference to a bottle carrier made from a single blank of die-cut and scored paper-board material, folded and secured in collapsed condition and which, after being opened and once used, is intended to be disposed of by the user.

Generally, it is an object of the invention to provide such a bottle carrier that is economic of manufacture, simple, but sufficiently durable and attractive, and otherwise well suited to the purposes for which it is intended.

Specifically, it is an object of the invention to provide a bottle carrier made from a single blank of paper-board material which provides uninterrupted side and end walls for maximum advertising space, maximum protection between longitudinal and transverse partitions positively to prevent bottles from touching, thereby avoiding so-called bottle click, by the construction and arrangements of such partitions, and to provide a stronger carrier, more neat in appearance, with the bottle tops flush with the top of the handle carrying section, thus making vertical stacking possible while still exposing a substantial portion of all of the bottles and labels equally and to the same extent.

More specifically, it is an object of the invention to provide a single die-cut and scored blank of paper-board material to be folded and secured together in collapsed form for use, when opened, as a non-returnable bottle carrier, comprising a rectangularly shaped panel divided into two identical portions along a transverse fold line to provide connected, integral longitudinal partition sections and inner carrying handle sections, securable to each other, a transverse partition section cut from each longitudinal partition section securable to an opposite side wall, each carrying handle section having a hand-hole therein, a first elongated panel section laterally extending from the same side of each longitudinal partition section which is also divided along transverse score lines and foldable into an end wall, an end wall extension and a transverse partition securable to an opposed longitudinal partition section, the end wall extension being securable to an opposed side wall section, a second elongated panel section extending from the other edge of each longitudinal partition section, and likewise being foldable along a transverse score line into an opposite end wall section and a side wall, a foldable bottom wall, and a third elongated panel section foldable along a second transverse score line into outer carrying handle sections and securable to the inner carrying handle sections.

Other objects of the invention will in part be obvious and will in part appear hereinafter.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention reference should be had to the following

2

detailed description taken in connection with the accompanying drawings, in which:

Fig. 1 is a plan view of a die-cut and scored blank embodied by the invention;

5 Fig. 2 illustrates the blank of Fig. 1 once folded upon itself;

Fig. 3 illustrates the blank of Fig. 2 again folded upon itself;

10 Fig. 4 represents the blank of Fig. 3 again folded upon itself;

Fig. 5 shows the blank of Fig. 4 folded and secured in final collapsed shipping condition;

Fig. 6 depicts the collapsed bottle carrier of Fig. 5 opened or squared to receive bottles;

15 Fig. 7 is a top view of Fig. 6;

Fig. 8 is a transverse vertical sectional view taken along the lines 8—8 of Fig. 7 and looking in the direction of the arrows;

20 Fig. 9 is a longitudinal vertical sectional view taken along the lines 9—9 of Fig. 8 and looking in the direction of the arrows; and

Fig. 10 is a fragmentary perspective view of the bottom panel supporting hook.

Referring more particularly to the drawings, there is 25 indicated generally at 11 a preferred form of die-cut and scored blank embodied by the invention.

The blank 11 comprises a central, rectangularly shaped panel indicated at 12 and is divided into two identical portions 13 and 14 along a transverse score line 15.

30 Each portion 13 and 14 is composed of integral, longitudinal partition sections 16 and 17 and inner carrying handle sections 18 and 19, foldable along the score line 15 and securable to each other, as will more fully appear hereinafter.

35 A transverse partition section 20 is centrally cut from each longitudinal partition section 16 and 17 around the line 21, but hingedly connected to each longitudinal partition section along the score line 22. Each transverse partition section 20 is defined by the score line 22 and score line 23 and terminates in a glue flap 24 so that the same is T-shaped in configuration.

40 Each identical portion 13 and 14 also has a cut-out corner portion indicated at 25 providing a hook 26 for supporting the bottom panel or wall as will more fully appear hereinafter.

45 An elongated panel section, indicated generally at 27, laterally extends from the same side or edge of each longitudinal partition section 16 and 17 along the score line 28. Each panel section 27 is divided along transverse

50 score lines 28 and transverse score lines 29, 30 and 31 into an end wall section 32, an end wall extension 33, a first transverse partition section 34 and a glue flap 35, the latter being securable to an opposed longitudinal partition section, each end wall extension 33 being securable to an opposed side wall section as will more fully appear hereinafter.

55 A second elongated panel section indicated generally at 36 laterally extends from the opposite side of each longitudinal partition section 16 and 17 beginning along the transverse score line 37. Each panel section 36 is divided along score line 37 and transverse score line 38 into end walls 39 and side walls 40. One side wall 40 preferably has a glue flap 41 thereon hinged along the score line 42, and the other side wall 40 has a bottom

60 panel or wall indicated generally at 43 hinged thereto along the score line 44. The bottom 43 also has a transverse score line 45 terminating in a cut-out portion 46 for the purpose of receiving the hooks 26 as will more fully appear hereinafter. The score line 45 enables the

65 bottom wall or panel to be folded upon itself.

66 The carrying handle sections 18 and 19 of the identical portions 13 and 14 of the elongated panel 12 have hand-

holes 47 therein and, as will appear hereinafter, these hand-holes will be brought into alignment when the portions 13 and 14 are adhesively secured to each other, thereby forming inner carrying handle sections as part of a double wall longitudinal partition.

A third elongated panel section 48 laterally extends from the handle carrying sections 18 and 19 between the end walls 39 and side walls 40 from which they have been cut free. The elongated panels 48 are defined by the score line 37, cut or severance lines 49 and 50, and transverse score line 51, the latter being in coaxial alignment with the score line 15 which divides the panel 12 into identical portions 13 and 14. Also, each panel 48 has hand-holes corresponding to the hand-holes 47, and are defined by a line of severance 52 to form hand-holding flaps 53 hinged along score lines 54. All of the hand-holes ultimately are brought into alignment and, as will also more fully appear hereinafter, the panels 48, when secured to the hand-holding sections 18 and 19, provide outer carrying handle sections.

The blank 11 thus die-cut and scored is run through a line gluing machine where spots of glue preferably are applied as indicated by the stippling on opposite sides of the transverse partitions 20 of the longitudinal partition sections 16 and 17 as indicated at 55. Such glue spots are for the reception of the glue flaps 35 and should be understood that the same could likewise be applied to such glue flaps if desired. As the blank continues through the machine, the transverse partition sections 20 are raised upwardly around the score lines 22, the panels 27, folded along score lines 29, and the glue flaps 35 tucked underneath the transverse partitions 20 to be secured to the longitudinal partition sections 16 and 17, thereby partly bridging the gap or opening left by the cut-out transverse partitions 20 which prevents bottles on opposite sides of the longitudinal partition, or double wall, from clicking. In this condition the blank is folded as illustrated in Fig. 2.

The folded blank in the form shown in Fig. 2 continues through the machine where glue is applied, as shown by the stippling 56 on the glue flaps 24, 57 on the panels 48, and 58 on the side walls 40. The left side of the folded blank is then folded over along the score line 37 so that the end wall extensions 33 are secured to the side walls 40 by means of the glue 58. At the same time the inner carrying handle sections 18 and 19 will be secured to the outer carrying handle sections 48 by means of the glue 57. Also, the glue flaps 24 on the transverse partitions 20 will become secured to the side walls 40. The blank thus far folded and secured is shown in Fig. 3. As the folded blank shown in Fig. 3 continues through the machine, glue is applied as shown by the stippling 59, preferably on the back of one of the panels, for example, identical portion 19. The thus far folded blank is once again folded along the score line 15 and underlying score line 51 so that the identical panel portion 18 becomes laminated to the panel portion 19 to form a double longitudinal partition. At this point all of the hand-holes will be secured in aligned position so that the hand-hole flaps 53 can be swung around the score lines 54, outwardly and upwardly to form a carrying handle grip of substantial thickness and strength. At the same time glue could have been applied to the glue flap 41 on the side wall 40. However, it might also be applied to the folded blank as shown in Fig. 4 by the stippling 60. Thereupon, the bottom wall or panel 43 is folded upon itself along the score line 45 and secured to the glue flap 41 to provide a collapsed bottle carrier as shown in Fig. 5.

Upon squaring or opening the collapsed carrier of Fig. 5, it will readily and quickly assume the position shown in Fig. 6, and Figs. 7, 8 and 9. The hooks 26 are then made to engage the bottom wall 43 in the area of the cut-out portion 46 to lend additional support to the bottom and the carrier is ready to be filled with bottles.

It will thus be seen that the objects hereinbefore set forth

may readily and efficiently be attained, and since certain changes may be made in the above article and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention what I claim as new and desire to secure by Letters Patent is:

- 15 1. A single die-cut and scored blank of paper-board material to be folded and secured together in collapsed form for use, when opened, as a non-returnable bottle carrier, which comprises a rectangularly shaped panel divided into two identical portions along a first transverse score line to provide two connected, integral longitudinal partition sections and inner carrying handle sections, foldable along said score line and securable to each other; a T-shaped transverse partition section centrally cut from within the confines of each longitudinal partition section, and providing a T-shaped opening therein, but hingedly connected thereto and securable to an opposite side wall of said carrier, each carrying handle section having a hand-hold therein adjacent said T-shaped opening; a first elongated panel section laterally extending from the same side of each longitudinal partition section, each said first panel section being divided along transverse score lines into an end wall section, an end wall extension, a transverse partition section as wide as its end wall section and as long as a side wall, and a glue flap respectively, the latter being securable to an opposed longitudinal partition section centrally to overlie said T-shaped opening as a barrier between opposed bottles, and said end wall extension being securable to an opposed side wall section; a second elongated panel section laterally extending from the opposite side of each longitudinal partition section, each said second panel section being divided along a transverse score line into an opposite end wall section and a side wall; a bottom panel hingedly connected to the bottom of one of said side walls and securable to the bottom of the opposite side wall; and a third elongated panel section laterally extending from said handle carrying sections, between each said second panel section and being severed therefrom and from said adjacent end wall section, said third panel being divided by a second transverse score line, coaxial with said first transverse score line, into outer carrying handle sections, having hand-holes therein, foldable along said second transverse score line, and securable to said inner carrying handle sections with all said hand-holes in alignment.
- 20 2. A collapsed bottle carrier made from a single die-cut, scored and folded blank of paper-board material secured together, which, when opened, forms a non-returnable bottle carrier, comprising a rectangularly shaped panel divided into two identical portions along a first transverse score line to provide two connected, integral longitudinal partition sections and inner carrying handle sections, folded along said score line and laminated to each other to form a double wall longitudinal partition and carrying handle section; a first T-shaped transverse partition section centrally cut from within the confines of each longitudinal partition section, and providing a T-shaped opening therein, but hingedly connected thereto and hingedly secured to an opposite side wall of said carrier, and folded thereagainst, each carrying handle section having a hand-hole in alignment, one with the other adjacent said T-shaped opening; a first elongated panel section extending from the same side of each longitudinal partition section being divided along transverse score lines and folded into an end wall section, an end wall extension, a second transverse partition sec-

tion as wide as its end wall section and as long as a side wall, and a glue flap respectively, the latter being tucked under the first transverse partition section and secured against an adjacent longitudinal partition section centrally to overlie said T-shaped opening as a barrier between opposed bottles, and said end wall extension being secured to an adjacent side wall with said second transverse partition section folded between an opposed side wall and longitudinal partition section; a second elongated panel section extending from the opposite side of each longitudinal partition section, each said second panel section being divided along a transverse score line and folded into an opposite end wall section and side wall; a bottom panel hingedly connected to the bottom of one of said side walls, divided by a transverse score line into two portions overfolded upon each other, connected to the bottom of the opposite side wall; and a third elongated panel section extending from said handle carrying section severed from said second panel section and from the adjacent end wall section, and being divided by a second transverse score line, into outer carrying handle sections, having hand-holes therein, folded along said second score line which overlies said first transverse score line, and said outer carrying handle sections being laminated to said inner carrying handle sections with all hand-holes in alignment.

3. A collapsible, non-returnable bottle carrier, made from a single blank of paper-board material, die-cut, scored, folded and secured together into squared bottle carrying position, which comprises a rectangularly shaped panel divided into two identical portions along a first transverse score line to provide two connected, integral longitudinal partition sections and inner carrying handle sections, folded along said score line and laminated to each other to form a double wall longitudinal partition and carrying handle section; a first T-shaped transverse partition section centrally cut from within the confines of each longitudinal partition section, and providing a T-shaped opening therein, but hingedly connected thereto, laterally extending therefrom, and

5 10 15 20 25 30

hingedly secured to an opposite side wall spaced from said double wall of said carrier, each carrier handle section having a hand-hole in alignment, one with the other adjacent said T-shaped opening; a first elongated panel section extending from the same side of each longitudinal partition section, in opposite directions, each being divided along transverse score lines and folded in spaced relation into an end wall section, an end wall extension secured to a side wall, a hinged transverse second partition as wide as its end wall section and as long as a side wall extending laterally inwardly, and terminating in a glue flap hingedly secured to a longitudinal partition section centrally to overlie said T-shaped opening as a barrier between opposed bottles; a second elongated panel section extending from the opposite side of each longitudinal partition section, each said second panel section being divided along a transverse score line and folded in secured spaced relation to form opposite end wall sections and side walls; a bottom panel hingedly connected to the bottom of one side wall and hingedly secured to the bottom of the other side wall; and a third elongated panel section extending from said handle carrying section, severed from said second panel section and from the adjacent end wall section, and being divided by a second transverse score line, into outer carrying handle sections, having hand-holes therein, folded along said second score line which overlies said first transverse score line, and said other carrying handle sections being laminated to said inner carrying handle sections with all hand-holes in alignment.
